CONTROL APPARATUS FOR INTERNAL- COMBUSTION ENGINES

Leighton Lee, II, West Hartford, Conn., assignor,
by means assignments, to Niles-Bement-Pond
Company, West Hartford, Conn., a corporation
of New Jersey

Application January 16, 1946, Serial No. 641,577

15 Claims. (Cl. 123—139)

1
This invention relates to apparatus for controlling the supply of fuel to an internal combustion engine.

Fuel supply systems for internal combustion engines may, generally speaking, be classified either as carburetor type systems, in which the fuel is mixed with the air in the air induction system of the engine, after which the mixture is distributed through the intake manifold to the cylinders; or as distributor-type systems, wherein the fuel charge for the engine is broken up by a fuel distributor mechanism into small charges for the individual cylinders, and these charges are conveyed to the cylinders by suitable conduits. The present invention relates particularly to the distributor type of fuel supply system.

An object of the present invention is the provision of a novel distributor type fuel supply system for an internal combustion engine, including improved means for controlling the flow of fuel to the engine.

Another object is the provision of novel means of simple construction for effectively controlling the supply of fuel in a distributor type system, in response to both the rate of fuel flow and the rate of air flow to the engine.

The invention, in its more specific aspects, provides a member rotatable in a chamber to establish communication between a fuel supply pump and the distributor outlet ports in predetermined succession, said member being at the same time shiftable longitudinally into such position that the fuel differential pressure balances the air differential pressure. Such longitudinal shifting of said member does not vary the size of the distributor ports, but effects variation in the fuel flow to the engine by variation in the fuel pressure applied through the distributor ports to spring loaded injector nozzles in the engine cylinders.

A further feature of the invention is the control of fuel flow in a distributor type supply system through a member shiftable to control the by-passing of fuel from the outlet to the inlet side of the fuel pump.

Other features of the invention will be herein-after described and claimed.

In the accompanying drawings:

Fig. 1 is a view in longitudinal vertical section

2
Illustrating a combined pump and distributor apparatus embodying my invention.

Fig. 2 is a diagrammatic view, with parts in section, showing the apparatus of Fig. 1 in combination with connections for control of the same by the differential pressure of air flowing to the engine.

Referring to the drawings, the fuel control mechanism 10 includes (as shown in Fig. 1) a housing 12 which contains a pump 14 of generally conventional design. The pump comprises a rotor 16 having the usual blades 17, and driven by a shaft 18 which is splined at its end so that it may readily be driven through a suitable connection from the engine. Fuel is received by the pump through an inlet connection 20 and is discharged through an outlet 22.

A by-pass valve arrangement of known construction is provided, comprising a valve element 24 which fits into a bore 25 in the member 26, the latter being threaded into a top portion of the housing 12. Openings such as indicated at 27 provide communication between the pump inlet 20 and the portion of the bore 25 above the valve 24.

Normally, a spring 28 maintains said valve 24 in its uppermost position wherein it prevents passage of fuel downwardly through the bore 25. If, however, the pump inlet pressure for any reason exceeds the discharge pressure by a predetermined amount, the valve 24 opens, permitting fuel to by-pass the pump rotor 16, and to flow from the inlet 20 past the valve, through chamber 29, and thence directly to the outlet 22. This arrangement is useful when two pumps are connected in series in a fluid line. If one pump fails to operate for some reason, the by-pass valve on that pump opens to allow the other pump to move fuel past it. Such by-pass arrangement is well-known, and no novelty is claimed therefor in this application.

The end of the pump rotor 16 opposite the shaft 18 is drivingly connected to a piston 30, which is mounted for both rotary and translatory motion in a bearing sleeve 32 fitted within an extension of the housing 12. The driving connection between the rotor 16 and piston 30 may take any suitable form for effecting rotation of said piston while at the same time permitting translation thereof. Said connection may, as

shown, comprise a pinion 34 driven by the rotor 16 meshing with an internal gear 36 on the piston 30, the teeth of said internal gear being of sufficient length to permit translation of the piston throughout its maximum range without disengagement of said gear 36 from said pinion 34. The piston may thus be continuously rotated with the pump rotor 16, while also being movable longitudinally in the sleeve 32.

Rotation of the pump rotor 16 draws fuel from a suitable tank or reservoir through a conduit 38 (Fig. 2) and opening 20 (Fig. 1) and impels said fuel through discharge opening 22 into channel 40. The latter communicates at one end with said discharge opening 22 and at its opposite end, through passage 42, with an annular chamber 44 formed in portions of the housing 12 and bearing 32 and surrounding the lefthand portion of the piston 30. A suitable restriction is provided in the channel 40, such as that illustrated at 46.

The annular fuel-receiving chamber 44 communicates, through openings 38 provided in the bearing sleeve 32, with an annular chamber 48 in the piston 30. A longitudinal slot 50 is said piston provides communication between said chamber 48 and a plurality of circumferentially spaced ports extending through the bearing sleeve 32, two of which ports are shown at 52. Thus, as said piston rotates, said circumferentially spaced ports are brought successively into communication with the fuel-containing chamber 48.

Each of the circumferentially spaced ports above mentioned is connected by a corresponding one of a plurality of conduits 54 to a suitable injector nozzle in a corresponding cylinder of the engine or in the fuel intake passage thereof. Communication between each of said ports and a corresponding conduit 54 may conveniently be effected through an associated passage 56 in a wall of a casing 58 secured to the front end of the housing 12; each passage 56 in turn communicating with the associated conduit 54 through a restriction 60. These restrictions are removable, and by varying the relative sizes of the several restrictions, may be utilized to increase the amount of fuel flow to one or more of the cylinders relative to the amount supplied to the other cylinders.

The injector nozzles may be of any suitable or well-known spring-loaded type. One form of nozzle which may be employed is shown at 62, comprising a valve head 64 carried by a stem 66, and biased to closed position by a spring 68. When fluid under pressure is supplied to the conduit 54 this pressure is communicated to the chamber 10 within the nozzle 62, and acts upon the valve head 64 to open the latter. If the pressure in line 54 increases, the valve will open wider, compressing the spring 68 further and relieving the increased pressure. Since this type of injector nozzle is well-known, further description thereof is unnecessary. In Fig. 1, the portion 54' of the conduit 54 adjacent the nozzle 62 is shown, for convenience, on a smaller scale than the portion of said conduit adjacent the casing 58.

It will be noted that the piston notch 50 is open at its outer end so that fuel may flow continuously from piston chamber 48 into the chamber 72 within the bearing sleeve 32 at the left of said piston. The latter is thus subjected at opposite ends to the differential pressure of fluid flowing through the restriction 46. Furthermore, by providing for flow of fuel from the chamber 48 independently of the position of the slot 50 with relation to the passages 52, objectionable puls-

tions of fuel pressure during rapid rotation of said piston are prevented.

The casing 58 contains a flexible diaphragm 14, which separates said casing into a pair of chambers 76 and 78. Port 80 in chamber 76 is connected by a conduit 82 to one or more impact tubes 84 (Fig. 2) in the path of air flowing into the passage 86 on its way to the engine manifold. Port 88 in chamber 78 is connected to a Venturi restriction 90 in said passage, through a conduit 82.

The diaphragm 14 is connected to piston 30 by any suitable means whereby movement of the diaphragm in either direction is imparted to said piston, without interfering with continuous rotation of the piston. One such means which may be employed to advantage is illustrated in Fig. 1, wherein a recessed member 94 passes through the center of the diaphragm and is pinned or otherwise suitably secured thereto. Mounted near one end in a bearing 96 in said member 94 is a shaft 98 which throughout the greater portion of its length extends through a bearing sleeve 100. At the opposite end, said shaft 98 is provided with a recessed head 102 having one or more fingers engaging openings or slots in lugs on the piston 30, one of which lugs is shown at 104, so that said shaft rotates with said piston and also transmits longitudinal movement thereto in response to movement of the diaphragm 14.

The conduit 82 is shown communicating with a chamber 106 (Fig. 2), which chamber communicates through conduit 108 with the throat of the venturi 90. The conduit 82, which receives the total or dynamic pressure of the air at the venturi entrance, communicates with the chamber 106 through a passage containing a restriction 110 and also controlled by a valve 112 positioned by a bellows 114 in said chamber 106. The function of said valve 112 and bellows 114 is to reduce the total pressure differential produced by venturi 90 by an amount sufficient to correct for decrease in density of the air due to altitude or temperature, so that the pressure drop appearing across the restriction 110 is a measure of the mass of air flowing through the venturi per unit of time. Since the pressure drop across said restriction 110 is applied to the diaphragm 14, it will be apparent that said diaphragm is subject to a force which is a measure of the rate of said mass air flow.

Formed in the righthand end of the bearing sleeve 32, and in the surrounding portion of the housing 12, is an annular chamber 116. The latter is in constant communication with the bore 25 and the pump inlet 20 through channel 118 and openings 27. Said chamber 116 is also in constant communication with openings 120 extending through the righthand portion of said sleeve 32.

The righthand end of the piston 30 is cut away above the gear 36 so that when said piston is in the position shown in Fig. 1, some of the fuel emerging from the pump discharge outlet 22 will return to the pump inlet by way of chamber 28, openings 120, chamber 116, passage 118, and openings 27. Movement of the piston further to the left increases the area of the openings or ports 120 for said return flow of fuel; while movement of said piston to the right decreases said port area. When the piston moves sufficiently to the right, it completely cuts off said ports 120 and prevents fuel from flowing back from the pump outlet 22 to the inlet 20.

In the operation of the apparatus above de-

scribed, the differential pressure corresponding to the mass air flow to the engine per unit of time urges the diaphragm 74 and piston 30 to the right; while the fuel pressure differential across the restriction 48, which is a measure of the rate of fuel flow to the engine, acts upon said piston to urge the latter to the left. Under normal conditions of operation, the piston will be in the position shown in Fig. 1, with communication established between outlet 22 and inlet 20 by way of passage 118; since the pump capacity at any given engine speed is normally much greater than any fuel flow that would be required at that speed. If, now, the rate of air flow rises, the differential pressure in the chambers 78 and 76 becomes greater and shifts the piston 30 to the right, reducing the back flow of fuel from outlet 22 to inlet 20. Thus the fuel flow to the chamber 72 at the left of the piston 30 is increased, producing an increased pressure in said chamber; and this increased pressure acts upon the respective injector valves 64 during the rotation of the piston to open said valves further against the action of their springs and thereby increase the flow of fuel to the respective engine cylinders. The fuel differential pressure acting upon the piston 30 is also increased, and urges the piston to the left, so that said piston comes to rest in a position wherein the pressure exerted on the piston by said fuel pressure differential balances that of the increased air pressure differential. If, now, the air flow decreases, the fuel pressure differential moves the piston 30 further to the left, increasing the back flow of fuel to the pump inlet and decreasing the fuel flow through the chamber 72 and injector nozzles 62, until the piston reaches a position wherein the consequent decreased fuel-pressure differential balances the diminished air-pressure differential.

It will thus be apparent that, through the apparatus above described, there is maintained a substantially constant ratio between the fuel flow and the air flow.

It will also be seen that, through the above described apparatus, an increase of pump discharge pressure when the piston 30 is in balanced position will move said piston to the left from said position, allowing further flow of fuel back to the pump inlet and relieving said discharge pressure. Said piston continues to open wider the path of return fuel flow through openings 120, until the discharge pressure is reduced to such value that the fuel pressure differential is balanced by the air pressure differential. Thus, for a given air differential pressure the pump discharge pressure is maintained substantially constant; and this is achieved through the same elements that maintain a substantially constant ratio between the fuel and air flows, and without the necessity of a separate pump discharge pressure relief valve.

If desired, a spring 122 may be provided for urging the diaphragm 74 to the right in Fig. 1 to insure that back flow of fuel through the relief passage 116 is restricted to any preferred extent when no air is flowing through the venturi 100 or when the air differential pressure is very small, as for low rates of air flow corresponding to idling positions of the throttle.

The pressure of spring 122 on the diaphragm 74 may be adjusted as desired by conventional spring-adjusting means, such as a nut 124 and screw 126.

The rotation of the piston 30 throughout the operation of the engine not only places the re-

spective injector nozzles of the engine cylinders in communication with the fuel chamber 44 in predetermined succession, but also eliminates static friction between the piston and the bearing sleeve 32. The piston is thus enabled to respond with particular accuracy and precision to slight changes in the air and fuel pressure differentials.

The terms and expressions which I have employed are used as terms of description and not of limitation, and I have no intention, in the use of such terms and expressions, of excluding any equivalents of the features shown and described or portions thereof, but recognize that various modifications are possible within the scope of the invention claimed.

I claim:

1. A fuel control system for an internal combustion engine, comprising a chamber having ports for the discharge of fuel to the respective cylinders of said engine, rotary means in said chamber for placing said ports successively in communication with a fuel supply, a fuel pump having a fuel inlet and a fuel discharge outlet, a portion of said rotary means being exposed to the pressure of fuel emerging from said outlet, restricted-passage means for conducting fuel from said outlet to another portion of said rotary means whereby the latter receives fuel for distribution to said cylinders and is subjected to the differential pressure of fluid flowing through said restricted passage means, said rotary means being movable longitudinally in said chamber in response to variations in said fuel differential pressure, and other passage means controlled by longitudinal movement of said rotary means for providing a path for the flow of fuel from said pump discharge outlet to said pump inlet.

2. A fuel control system for an internal combustion engine, comprising a chamber having ports for the discharge of fuel to the respective cylinders of said engine, rotary means in said chamber for placing said ports successively in communication with a fuel supply, a fuel pump having a fuel inlet and a fuel discharge outlet, a portion of said rotary means being exposed to the pressure of fuel emerging from said outlet, restricted-passage means for conducting fuel from said outlet to another portion of said rotary means whereby the latter receives fuel for distribution to said cylinders and is subjected to the differential pressure of fluid flowing through said restricted passage means, said rotary means being movable longitudinally in said chamber in response to variations in said air and fuel differential pressures, and other passage means controlled by longitudinal movement of said rotary means for providing a path for the flow of fuel from said pump discharge outlet to said pump inlet.

3. Fuel control apparatus for an internal combustion engine having spring-loaded fuel injector nozzles, said apparatus comprising a control chamber having ports therein for the discharge of fuel to said nozzles, a member rotatable in said chamber for placing said ports successively in communication with a fuel supply, a fuel pump having a fuel inlet and a fuel discharge outlet, a portion of said member being exposed to the pressure of fuel emerging from said outlet, restricted passage means for conducting fuel from said outlet to another portion of said rotary member whereby the latter receives fuel for dis-

tribution to said nozzles and is subjected to the differential pressure of fluid flowing through said restricted passage means, said member being movable longitudinally in said chamber in response to variations in said fuel differential pressure, and means controlled by longitudinal movement of said member for providing a path for the flow of fuel from said pump discharge outlet to said pump inlet.

4. Fuel control apparatus for an internal combustion engine having spring-loaded fuel injector nozzles, said apparatus comprising a control chamber having ports therein for the discharge of fuel to said nozzles, a member rotatable in said chamber for placing said ports successively in communication with a fuel supply, a fuel pump having a fuel inlet and a fuel discharge outlet, a portion of said member being exposed to the pressure of fuel emerging from said outlet, restricted passage means for conducting fuel from said outlet to another portion of said rotary member whereby the latter receives fuel for distribution to said nozzles and is subjected to the differential pressure of fluid flowing through said restricted passage means, means connected to said member for subjecting the latter to the differential pressure of air flowing to the engine, said member being movable longitudinally in said chamber in response to variations in said air and fuel differential pressure, and means controlled by longitudinal movement of said member for providing a path for the flow of fuel from said pump discharge outlet to said pump inlet.

5. Fuel control apparatus for an internal combustion engine having spring-loaded fuel injector nozzles, said apparatus comprising a control chamber having ports therein for the discharge of fuel to said nozzles, a rotary and longitudinally movable piston in said chamber having a passage therein adapted to be brought into communication with said ports successively during rotation of said piston, means having a restriction therein for supplying fuel to said passage, said passage in said piston being open at one end to the adjacent portion of said chamber for supplying thereto fuel at a pressure lower than the fuel pressure upstream of said restriction, the portion of said chamber adjacent the opposite end of said piston being open to said upstream fuel pressure, and said piston passage being of sufficient length to maintain substantially unchanged communication with said discharge ports despite longitudinal movements of said piston in response to variations in the differential pressure of the flowing fuel.

6. Fuel control apparatus for an internal combustion engine having spring-loaded fuel injector nozzles, said apparatus comprising a control chamber having ports therein for the discharge of fuel to said nozzles, a rotary and longitudinally movable piston in said chamber having a passage therein adapted to be brought into communication with said ports successively during rotation of said piston, means having a restriction therein for supplying fuel to said passage, said passage in said piston being open at one end to the adjacent portion of said chamber for supplying thereto fuel at a pressure lower than the fuel pressure upstream of said restriction, the portion of said chamber adjacent the opposite end of said piston being open to said upstream fuel pressure, and said piston passage being of sufficient length to maintain substantially unchanged communication with said dis-

charge ports despite longitudinal movements of said piston in response to variations in the differential pressure of the flowing fuel, and means responsive to longitudinal movement of said piston for controlling the pressure of the fuel supplied to said discharge ports.

7. Fuel control apparatus for an internal combustion engine having spring-loaded fuel injector nozzles, said apparatus comprising a control chamber having ports therein for the discharge of fuel to said nozzles, a rotary and longitudinally movable piston in said control chamber, the longitudinal movement of said piston being adapted to effect variations in fuel flow by varying the fuel pressure applied through said ports, a fuel-receiving chamber surrounding said control chamber and having communication with an interior chamber in said piston, said piston having a discharge slot in communication with said interior chamber and adapted to be brought into communication with the aforementioned ports successively during rotation of said piston, and means for supplying fuel to said fuel-receiving chamber.

8. Fuel control apparatus for an internal combustion engine having spring-loaded fuel injector nozzles, said apparatus comprising a control chamber having ports therein for the discharge of fuel to said nozzles, a rotary and longitudinally movable piston in said control chamber, the longitudinal movement of said piston being adapted to effect variations in fuel flow by varying the fuel pressure applied through said ports, a fuel-receiving chamber surrounding said control chamber and having communication with an interior chamber in said piston, said piston having a discharge slot in communication with said interior chamber and adapted to be brought into communication with the aforementioned ports successively during rotation of said piston, means having a restriction therein for supplying fuel to said fuel-receiving chamber, said piston slot being open at one end for supplying fuel to the adjacent portion of the control chamber whereby an end of said piston is subject to fuel pressure downstream of said restriction, the portion of said control chamber adjacent the opposite end of said piston being open to fuel pressure upstream of said restriction, and said piston slot being of sufficient length to maintain substantially unchanged communication with said discharge ports despite longitudinal movements of said piston in response to variations in the differential pressure of the flowing fuel.

9. Fuel control apparatus for an internal combustion engine having spring-loaded fuel injector nozzles, said apparatus comprising a control chamber having ports therein for the discharge of fuel to said nozzles, a rotary and longitudinally movable piston in said chamber having a passage therein adapted to be brought into communication with said ports successively during rotation of said piston, a fuel pump having a fuel inlet and a fuel discharge outlet, means having a restriction therein for supplying fuel from said outlet to said piston passage, said passage in said piston being open at one end to the adjacent portion of said chamber for supplying fuel thereto at a pressure lower than that upstream of said restriction, the portion of said chamber adjacent the opposite end of said piston being open to said upstream fuel pressure, said piston passage being of sufficient length to maintain substantially unchanged communication with said discharge ports despite longitudinal movements of

said piston in response to variations in differential pressure of the flowing fuel and means controlled by longitudinal movement of said piston for providing a path for return flow of fuel from said pump outlet to said pump inlet.

10. Fuel control apparatus for an internal combustion engine having spring-loaded fuel injector nozzles, said apparatus comprising a control chamber having ports therein for the discharge of fuel to said nozzles, a rotary and longitudinally movable piston in said chamber having a passage therein adapted to be brought into communication with said ports successively during rotation of said piston, a fuel pump having a fuel inlet and a fuel discharge outlet, means having a restriction therein for supplying fuel from said outlet to said piston passage, said passage in said piston being open at one end to the adjacent portion of said chamber for supplying fuel thereto at a pressure lower than that upstream of said restriction, the portion of said chamber adjacent the opposite end of said piston being open to said upstream fuel pressure, means connected to said piston for subjecting the latter to a force corresponding to the differential pressure of air flowing to the engine, said piston passage being of sufficient length to maintain substantially unchanged communication with said discharge ports despite longitudinal movements of said piston in response to variations in differential pressure of the flowing air and fuel and means controlled by longitudinal movement of said piston for providing a path for return flow of fuel from said pump outlet to said pump inlet.

11. Fuel control apparatus for an internal combustion engine having spring-loaded fuel injector nozzles, said apparatus comprising a control chamber having ports therein for the discharge of fuel to said nozzles, a rotary and longitudinally movable piston in said control chamber, a fuel-receiving chamber surrounding said control chamber and having communication with an interior chamber in said piston, said piston having a discharge slot in communication with said interior chamber and adapted to be brought into communication with the aforementioned ports successively during rotation of said piston, a fuel pump having a fuel inlet and a fuel discharge outlet, means having a restriction therein for conducting fuel from said outlet to said fuel-receiving chamber, said piston slot being open at one end for supplying fuel to the adjacent portion of said control chamber whereby an end of said piston is subject to fuel pressure downstream of said restriction, the portion of said control chamber adjacent the opposite end of said piston being open to fuel pressure upstream of said restriction, and means responsive to longitudinal movement of said piston for controlling return flow of fuel from said pump outlet to said pump inlet.

12. Fuel control apparatus for an internal combustion engine having spring-loaded fuel injector nozzles, said apparatus comprising a control chamber having ports therein for the discharge of fuel to said nozzles, a rotary and longitudinally movable piston in said control chamber, a fuel-receiving chamber surrounding said control chamber and having communication with an interior chamber in said piston, said piston having a discharge slot in communication with said interior chamber and adapted to be brought into communication with the aforementioned ports successively during rotation of said piston, a fuel pump having a fuel inlet and a fuel discharge

75

outlet, means having a restriction therein for conducting fuel from said outlet to said fuel-receiving chamber, said piston slot being open at one end for supplying fuel to the adjacent portion of said control chamber whereby an end of said piston is subject to fuel pressure downstream of said restriction, the portion of said control chamber adjacent the opposite end of said piston being open to fuel pressure upstream of said restriction, 5 said piston slot being of sufficient length to maintain substantially unchanged communication with said discharge ports despite longitudinal movements of said piston in response to variations in the differential pressure of the flowing fuel, and means responsive to longitudinal movement of said piston for controlling return flow of fuel from said pump outlet to said pump inlet.

13. Fuel control apparatus for an internal combustion engine having spring-loaded fuel injector nozzles, said apparatus comprising a control chamber having ports therein for the discharge of fuel to said nozzles, a rotary and longitudinally movable piston in said control chamber, a fuel-receiving chamber surrounding said control chamber and having communication with an interior chamber in said piston, said piston having a discharge slot in communication with said interior chamber and adapted to be brought into communication with the aforementioned ports successively during rotation of said piston, a fuel pump having a fuel inlet and a fuel discharge outlet, means having a restriction therein for conducting fuel from said outlet to said fuel-receiving chamber, said piston slot being open at one end for supplying fuel to the adjacent portion of said control chamber whereby an end of said piston is subject to fuel pressure downstream of said restriction, the portion of said control chamber adjacent the opposite end of said piston being open to fuel pressure upstream of said restriction, means connected to said piston and subject to a differential pressure corresponding to the rate of air flow to the engine for acting upon said piston in a direction opposite to that in which the fuel differential pressure acts upon said piston, and means responsive to longitudinal movement of said piston for controlling said fuel differential pressure.

14. Fuel control apparatus for an internal combustion engine having spring-loaded fuel injector nozzles, said apparatus comprising a control chamber having ports therein for the discharge of fuel to said nozzles, a rotary and longitudinally movable piston in said control chamber, a fuel-receiving chamber surrounding said control chamber and having communication with an interior chamber in said piston, said piston having a discharge slot in communication with said interior chamber and adapted to be brought into communication with the aforementioned ports successively during rotation of said piston, a fuel pump having a fuel inlet and a fuel discharge outlet, means having a restriction therein for conducting fuel from said outlet to said fuel-receiving chamber, said piston slot being open at one end for supplying fuel to the adjacent portion of said control chamber whereby an end of said piston is subject to fuel pressure downstream of said restriction, the portion of said control chamber adjacent the opposite end of said piston being open to fuel pressure upstream of said restriction, means connected to said piston and subject to a differential pressure corresponding to the rate of air flow to the engine for acting upon said piston in a direction opposite to that

11

in which the fuel differential pressure acts upon said piston, and means responsive to longitudinal movement of said piston for controlling the return of fuel from said pump outlet to said pump inlet.

15. Fuel control apparatus for an internal combustion engine having spring-loaded fuel injector nozzles, said apparatus comprising a control chamber having ports therein for the discharge of fuel to said nozzles, a rotary and longitudinally movable piston in said chamber having a passage therein adapted to be brought into communication with said ports successively during rotation of said piston, means having a restriction therein for supplying fuel to said passage, said passage in said piston being open at one end to the adjacent portion of said chamber for supply thereof to fuel at a pressure lower than the fuel pressure upstream of said restriction, the portion of said chamber adjacent the opposite end of said piston being open to said upstream fuel pressure, means connected to said piston and subject to a differential pressure corresponding to the rate

12

of air flow to the engine for acting upon said piston in a direction opposite to that in which the fuel differential pressure acts upon said piston, said piston passage being of sufficient length to maintain substantially unchanged communication with said discharge ports despite longitudinal movements of said piston, and means responsive to longitudinal movement of said piston pursuant to change in said air or fuel differential pressure for varying the pressure of the fuel supplied to said discharge ports.
